UNITED STATES PATENT OFFICE.

ANTON VAN VEEN, OF WEST HARTFORD, CONNECTICUT, ASSIGNOR TO THE FULLER BRUSH COMPANY, OF HARTFORD, CONNECTICUT, A CORPORATION OF CONNECTICUT.

MACHINE FOR TWISTING WIRES WITH MATERIAL THEREBETWEEN.

Application filed July 3, 1926 Serial No. 120,359.

This invention relates to the class of machines employed for twisting strands of cotton or other fibers between wires for the purpose of forming dust mops or similar articles, and an object of the invention, among others, is the production of a machine of this class that shall be particularly simple and efficient in its construction and operation.

One form of machine embodying my invention and in the construction and use of which the objects herein set out, as well as others, may be attained, is illustrated in the accompanying drawings, in which—

Figure 1 is a view in side elevation of one end of the upper part of a machine embodying this invention with the parts in position just before the clamping of the wires for a twisting operation.

Figure 2 is a similar view of the opposite end of the machine.

Figure 3 is a top view, scale reduced, but showing the position of the parts just after the clamping of the wires for a twisting operation.

Figure 4 is a view similar to Figure 3, but showing the position of the parts just after the completion of a twisting operation.

Figure 5 is a view on the same scale as Figures 3 and 4, but on a plane denoted by the dotted lines 5—5 of Figures 1 and 2, and with the parts in the same position as in Figure 3.

Figure 6 is a view similar to Figure 5, but with the position of the parts the same as in Figure 4.

Figure 7 is a view in vertical section through the mechanism shown in Figure 1 and on a plane passing through the axis of the chuck spindle.

Figure 8 is a top view of a portion of the tail stock showing the position of the parts as in Figure 3, portions being broken away to show construction.

Figure 9 is a similar view, but with the position of the parts as shown in Figure 4.

Figure 10 is a view in section of a portion of the machine on a plane denoted by the dotted line 10—10 of Figure 2, with the parts in position just prior to the twisting operation.

Figure 11 is a similar view of a portion of the machine shown in Figure 10, but with the mechanism in position just after the completion of the twisting operation.

Figure 12 is a detail view in rear elevation

illustrating the construction of the clutch mechanism.

Figure 13 is a view in section on a plane denoted by the dotted line 13—13 of Figure 12, with parts broken away to show construction.

Figure 14 is a similar view on a plane denoted by the dotted line 14—14 of Figure 12.

Figure 15 is another similar view on a plane denoted by the dotted line 15—15 of Figure 12.

The machine of which this invention forms a part is designed for the purpose of making dust mops, or similar articles, by the twisting of strands of cotton or other suitable material between wires constituting a core, the particular invention forming the subject matter of this case comprising mechanism for controlling the twisting operation, but in connection with the illustration of this mechanism other parts comprising the machine as a whole are shown to some extent, some of which parts are not specifically referred to in the description herein, but which parts will be found more specifically set forth and described in a copending application of Serial Number 120,358, filed July 3, 1926, to another invention embodied in the same machine, and to which reference is hereby made for such understanding as may be desired of parts shown herein but not specifically comprising a part of the present invention.

In the accompanying drawings the numeral 10 denotes the base of this improved machine having standards 11 rising therefrom and comprising the ends of the machine frame as a whole, said standards being connected by a beam 12 extending from one to the other of said standards and secured thereto at the upper portion thereof. A bracket 13 comprising uprights 14 is secured to the upper surface of the beam 12, this bracket in fact comprising the head stock of the machine and including a spindle 15 mounted for longitudinal movement in a clamp sleeve 16 having a flared end or mouth to receive chuck jaws 17 of spring formation secured to said spindle and adapted to be closed when drawn into the clamp sleeve by endwise movement of said spindle, in a manner that will be readily understood. Said clamp sleeve is rotatably mounted in bearings in the upper ends of the uprights 14 and a chuck jaw clamping collar 18 is mounted for endwise movement on said clamp sleeve.

to actuate jaw clamping levers 19 pivotally mounted in a clamp lever support 20 secured to an adjusting block 21 attached to the clamp sleeve 16. The levers 19 have heels 5 projecting through slots in the sleeve 16 to contact with lugs 22 projecting from opposite sides of the spindle 15, and by means of which endwise movement is imparted to the spindle by operation of the clamping collar 18 that is actuated by means of a flange projecting 10 into a groove in the collar from a jaw clamping slide 23 mounted for reciprocating movement on a bar 24 secured to and extending between the uprights 14, and as shown in Figure 7 of the drawings.

The slide 23 may be actuated as by means of a hand lever 25 pivotally mounted on the bracket 13 and having a toothed end in engagement with a rack on said slide, as shown 20 in Figure 1 of the drawings. The jaws 17 are adapted to grasp the ends of wires 26 between which the mass 27 of mop material has been placed in any desired manner, usually 25 by a mechanical operation, said wires and mass resting upon a table 28 pivotally supported by arms 29 extending upwardly from the front of the beam 12 and as shown in Figure 10 of the drawings. The table is connected by a rod 30 with a foot treadle 31, said 30 parts being held in their upward positions as by means of a spring 32, and the treadle being pivotally supported by the ends 11 of the main frame.

A tail stock 33 is mounted for sliding movement on the beam 12 at that end thereof opposite the head stock, said tail stock having a fixed holding jaw 34 and a pivoted holding jaw 35, the latter being operated as by means of a cam 36 on a jaw clamping shaft 37 to 40 clamp the ends of the wires 26 while being twisted, said shaft 37 being vertically mounted in the tail stock and having a pinion 38 in mesh with a rack at one end of a connecting rod 39 that also has a rack at its opposite end 45 in mesh with the teeth of a pinion 40 secured to a shaft 41 supporting the handle 25, from which it will be seen that the handle 25 is connected to simultaneously operate the clamping jaws on both the head and tail stocks. A handle 42 on the tail stock may 50 also be connected by a shaft 43 and intermeshing pinions, as shown in Figures 5 and 8, as a means for manual operation of the clamp jaws from the tail stock when such may be 55 desired.

The tail stock may be held at the backward limit of its movement by means of a weight 44 supported by a flexible connection passing over a sheave and attached to the tail stock, and a cushioning device 45 of any suitable construction may be employed, if desired, to retard movement of the tail stock backwardly.

This invention has much to do with the mechanism for controlling the winding operation of the machine hereinbefore de-

scribed, and to this end a driving pulley 46 is secured to a driving sleeve 47 rotatably mounted in a bearing in the upper end of one of the standards 11, and as shown in Figure 7 of the drawings, said pulley being driven 70 as by means of a belt 48 extending from any suitable source of power, as from a motor mounted on the frame of the machine. Said pulley has in its hub a recess to receive one member 49 of a twisting clutch, the other member 50 of said clutch being mounted on the spindle 15 and splined thereto to permit movement of said spindle endwise independently of the clutch member. This clutch is of the well known type of roller clutches and 80 that comprise rollers 51 mounted in wedge shaped spaces between the two clutch members and controlled in their movements by means of spacers 52 projecting from a clutch actuator 53 mounted on the clutch member 50 and independently rotatable thereon to a limited extent. This actuator has recesses 54 for springs 55, one end of each of said springs being secured to the actuator and the other end of each of said springs being secured to a flange 56 on the clutch member 50, whereby by the action of said springs said clutch member and actuator are caused to rotate in opposite directions to move the rollers 51 into the narrow part of the wedge shaped spaces and thereby connect the clutch members for simultaneous rotation. The actuator has a stop nose 57 positioned to engage a clutch disengaging lever 58 secured to a 90 rock shaft 59 mounted in bearings on the bracket 15 and having a clutch disengaging arm 60 containing a spring pressed plunger 61 pivotally attached to a clutch actuating finger 62 mounted on a pivot on the bracket 13 with its free end projecting into a hole in 100 a spring pressed clutch actuating rod 63 mounted for reciprocating movement in the bracket 13 and on the beam 12, as shown in Figures 1, 7 and 12 of the drawings.

A spring pressed clutch controlling rod 64 110 is mounted for endwise reciprocating movement on the beam 12 in the path of movement of the tail stock 33, and as shown in Figures 4 to 6, 8 and 9 of the drawings, the other end of said rod being adapted to encounter one 115 end of a clutch controlling lever 65 pivotally supported on the beam 12 and adapted to be engaged by a detent 66 projecting from a detent lever 67 pivotally supported on the beam 12 and with one end pivotally connected to 120 a clutch controlling plunger 68 spring pressed in one direction and mounted in a socket on the beam 12 and in the path of movement of the table 28, and as shown in Figure 7 of the drawings.

In the operation of the mechanism, the parts being in the position shown in Figures 1 and 2, two wires are in place with the mass 27 of mop material between them, the hand lever 25 will be swung to the left to the posi- 130

tion shown in Figures 3 and 4. This movement, aided by the mechanism hereinbefore described, will operate the slide 23 and jaw clamping levers 19 to close the chuck jaws 17, 5 and simultaneously, through the operation of the rod 39, the jaws 34—35 on the tail stock will be forced into contact with the wires to secure them to said tail stock, the wires just before this operation having been closed together in any desired manner, and especially 10 by the fingers of the operator. The treadle 31 being now depressed the table 28 will be lowered out of the path of the mop material during the twisting operation, and in its 15 downward movement the table will strike the plunger 68, thereby depressing it and swinging the lever 67 to move the detent 66 away from the lever 65. This will permit the spring on the rod 63 to move said rod to the left from 20 the position shown in Figures 1, 5, 6 and 7, thereby swinging the end of the lever 65 into the path of movement of the controlling rod 64. This movement of the rod 63 also operates to swing the disengaging lever 58, connected with the rod 63 as hereinbefore 25 described from under the nose 57 of the clutch actuator 53, thereby permitting the springs 55 to act upon the clutch member 50 and the actuator 53 to move the rollers 51 into the 30 narrow part of the wedge shaped space, thereby connecting the clutch members to effect rotation of the spindle 15 and parts including the jaws 17 carried thereby. The twisting of the wires causes them to be shortened 35 thereby moving the tail stock 33 toward the head stock and pushing the rod 64 toward and into contact with the lever 65 that at once starts to return as soon as the twisting operation begins being swung on its pivot to the 40 position shown in Figure 6. This operation shifts the rod 63 against the tension of its spring to the position shown in Figures 1, 3 to 7, and 12 of the drawings, thereby moving the clutch actuating mechanism into the 45 position shown in said figures whereby the end of the lever 58 is placed in the path of movement of the nose 57. The rotation of the spindle continues until the operation just described takes place, after which, as soon as the spindle completes its rotation, the nose 50 striking said lever will reverse the action of 55 the clutch parts hereinbefore described and the clutch members will be disengaged and the rotation of the spindle will cease. The treadle 31 having been released the detent 66 is located in the path of movement of the lever 65 to retain the parts in these positions, and the hold of the chuck jaws being released by 60 operation of the hand lever 25, the tail stock 65 will move back under the pull of the weight 44 in readiness for a repetition of the operation.

It is essential in the operation of the machine that the clutch jaws 17 stop with the 65 slot or space between them positioned ver-

tically so that the wires may be dropped into said slots. The chuck jaws will be in such proper position when the nose 57 of the actuator 53 is in contact with the lever 58. However, when in this position the tendency of 70 the twisted wires to untwist to some extent will influence backward movement of the clutch member 50 and thereby return movement of the rollers into the narrow part of the space occupied by them, whereas it is essential that the rollers shall remain in the wide part of said space until the next operation to connect the clutch members. 75

Owing to the rapid movement of the actuator 53 there is a tendency when the nose 57 strikes the end of the lever 58 for the actuator to bound backwardly and thus move the slot between the jaws from its vertical position. There is, therefore, provided, a detent mechanism to prevent any backward movement 80 of said parts either by bounding or by influence of the wires to untwist, this mechanism comprising a detent plate 69 mounted on the clutch member 50 and held against rotation as by pinning to an upright 14 of the bracket 85 90. Detent rollers 70 are located in wedge shaped recesses in the plate 69, as shown in Figure 15 of the drawings, and are engaged by spring pressed plungers 71 tending to force said rollers into the wider parts of said 95 recesses. When the nose 57 strikes the end of the lever 58 any tendency of the actuator to bound or otherwise move backwardly under influence of the twisted wire to move the clutch member 50 backwardly will at once be 100 resisted by the detent rollers, and they will immediately, by reason of such action be moved into the narrow part of the recesses, and such backward movement of either of 105 said members will be immediately checked.

It will be noted that the connection between the lever 58 and the rod 63 is such that when the arm 60 and finger 62 are swung so that their pivotal connecting point passes a line extending through the center of their pivotal 110 supports the action of the spring pressed plunger will cause the arm 60 and finger 62 to be moved quickly, the engagement of the end of the finger 62 in the enlarged socket in the rod 63 permitting this accelerated movement. 115

When the tail stock 33 is moved back, after a twisting operation to secure material between wires, and to its rearward position, as hereinbefore described, it is held against 120 forward movement until the twisting mechanism is again started, this being effected by means of a latch 72 pivotally supported by the beam 12 and having one end engaged with the tail stock to prevent such forward movement, the latch promptly engaging with the tail stock when it reaches its rearward position. The opposite end of the latch is positioned for engagement by a flange 73 on the rod 30 when the table 28 is moved downward, 125 130

this engagement of the latch by said flange removing the opposite end of the latch from the path of the tail stock and allowing the latter to move forward under the influence of 5 the shortening wires in the twisting operation, as hereinbefore described.

In accordance with the provisions of the patent statutes I have described the principles of operation of my invention, together 10 with the device which I now consider to represent the best embodiment thereof; but I desire to have it understood that the device shown is only illustrative and that the invention may be carried out by other means and 15 applied to uses other than those above set out.

I claim—

1. A wire twisting machine comprising a rotatable spindle having means for holding 20 wires to be twisted, a driving member mounted on said spindle, a clutch comprising clutch members between said driving member and spindle and including a stop movably mounted to effect release and engagement of said 25 clutch, means for imparting movement to said clutch, means for effecting one of said operations, and means governed by the twisting operation for effecting the other operation of said stop.

2. A wire twisting machine comprising a 30 rotatable spindle having means for holding wires to be twisted, a driving member mounted on said spindle, a clutch comprising clutch members between said driving member and spindle and including a stop movably mounted to effect release and engagement of said 35 clutch, manually actuated means for imparting movement to said stop to effect one of said operations, and means governed by the twisting operation for effecting the other operation 40 of said stop.

3. A wire twisting machine comprising a rotatable spindle having means for holding wires to be twisted, a driving member mounted on said spindle, a clutch comprising clutch 45 members between said driving member and spindle and including a stop movably mounted to effect release and engagement of said clutch, manually actuated means for effecting releasing movement of said stop for engagement of said clutch members, and means governed by the twisting operation for causing 50 disengagement of said clutch members.

4. A wire twisting machine comprising a rotatable spindle having means for holding 55 wires to be twisted, a driving member mounted on said spindle, clutch members for connecting said spindle and driving members, one of said clutch members being a rocking member having a shoulder, a stop movably mounted 60 to engage said shoulder, means for disengaging said stop and shoulder, and means governed by the twisting operation for placing said stop in the path of movement of said shoulder.

5. A twisting machine comprising a rotat-

able spindle having means for holding wires to be twisted, a driving member mounted on said spindle, clutch members for connecting said spindle and driving members, one of said clutch members being a rocking member having a nose, a stop movably mounted to engage 70 said nose, manually actuated means for disengaging said stop from said nose, and means governed by the twisting operation for placing said stop in the path of movement of said 75 nose.

6. A twisting machine comprising a rotatable spindle having means for holding wires to be twisted, a driving member mounted on 80 said spindle, clutch members for connecting said spindle and driving member, one of said clutch members being a rocking member having a shoulder, a stop lever pivotally mounted for engagement of one end with said shoulder, a sliding member operatively connected 85 with said lever, means for operating said slide to disengage said shoulder and stop member, and means governed by the twisting operation for placing said stop in the path of movement of said shoulder.

7. A twisting machine comprising a rotatable spindle having means for holding wires to be twisted, a driving member mounted on 90 said spindle, clutch members for connecting said spindle and driving member, one of said clutch members being a rocking member having a shoulder, a stop lever pivotally mounted for engagement of one end with said shoulder, a sliding member operatively connected 95 with said lever, an actuating member for said sliding member, and means governed by the twisting operation for placing said stop in the path of movement of said shoulder.

8. A twisting machine comprising a rotatable spindle having means for holding wires to be twisted, a driving member mounted on 100 said spindle, clutch members for connecting said spindle and driving member, one of said clutch members being a rocking member having a shoulder, a stop lever pivotally mounted for engagement of one end with said shoulder, a sliding member operatively connected 105 with said lever, an actuating member for said sliding member, manually operated means 110 for controlling operation of said actuating member, and means governed by the twisting operation for placing said stop in the path of movement of said shoulder.

9. A twisting machine comprising a rotatable spindle having means for holding wires to be twisted, a driving member mounted on 115 said spindle, clutch members for connecting said spindle and driving member, one of said clutch members being a rocking member having a shoulder, a stop lever pivotally mounted for engagement of one end with said shoulder, a sliding member operatively connected 120 with said lever, a controlling lever for said sliding member, a detent for holding said 125

controlling lever, means for releasing said detent for permitting movement of said controlling lever, and means governed by the twisting operation for placing said controlling lever out of the path of movement of said detent.

10. A twisting machine comprising a rotatable spindle having means for holding wires to be twisted, a driving member mounted on said spindle, clutch members for connecting said spindle and driving member, one of said clutch members being a rocking member having a shoulder, a stop lever pivotally mounted for engagement of one end with said shoulder, a sliding member operatively connected with said lever, a controlling lever for said sliding member, a detent for holding said controlling lever, means for releasing said detent to permit movement of said controlling lever, and means governed by the twisting operation for operating said controlling lever.

11. A twisting machine comprising a rotatable spindle having means for holding wires to be twisted, a driving member mounted on said spindle, clutch members for connecting said spindle and driving member, a pivotally mounted table, means for swinging said table on its pivots, means actuated by the swinging movement of said table and connected with one of said clutch members for actuation thereof, and means governed by the twisting operation for effecting another action of said clutch members.

12. A twisting machine comprising a rotatable spindle having means for holding wires to be twisted, a driving member mounted on said spindle, clutch members for connecting said spindle and driving member, a table movably mounted and adapted in one position to receive material to be twisted between said wires, means for moving said table away from said wires, a member located in the path of movement of said table and operatively connected with said clutch for actuation thereof, and means governed by the twisting operation to effect another action of said clutch.

13. A twisting machine comprising a rotatable spindle having means for holding wires to be twisted, a driving member mounted on said spindle, clutch members for connecting said spindle and driving member, means for disengaging said clutch members, means for stopping rotation of said spindle in a predetermined position, and means for preventing backward movement of a clutch member when disengaged.

14. A twisting machine comprising a rotatable spindle having means for holding wires to be twisted, a driving member mounted on said spindle, clutch members for connecting said spindle and driving member, one of said clutch members being a rocking member having a shoulder, means to engage said

shoulder to actuate said clutch members, with said wire holding means in a predetermined position and means to prevent backward movement of a clutch member during disengagement of said members.

15. A twisting machine comprising a rotatable spindle having means for holding wires to be twisted, a driving member mounted on said spindle, clutch members for connecting said spindle and driving member, one of said clutch members being a rocking member and having a shoulder, means to engage said shoulder to operate said clutch members, with said wire holding means in a predetermined position and means for preventing backward movement of said rocking clutch member when the clutch members are disengaged.

16. A twisting machine comprising a rotatable spindle having means for holding wires to be twisted, a driving member mounted on said spindle, clutch members for connecting said spindle and driving member, one of said clutch members being a rocking member and having a shoulder, means to engage said shoulder to disengage said clutch members, with said wire holding means in a predetermined position and detents engaged with said rocking member to permit forward movement, but to prevent backward movement thereof during disengagement of the clutch members.

17. A twisting machine comprising a rotatable spindle having means for holding wires to be twisted, a driving member mounted on said spindle, clutch members for connecting said spindle and driving member, one of said clutch members being a rocking member having an extension, a stationary member into which said extension projects, a tapered recess in said stationary member, and a detent located in said recess to prevent backward movement of the rocking clutch member.

18. A wire twisting machine comprising a rotatable spindle having means for holding wires to be twisted, a slidably mounted tail stock having means to hold said wires, means for retaining the tail stock in its backward position, and means for releasing said retaining means to permit forward movement of the tail stock.

19. A wire twisting machine comprising a rotatable spindle having means for holding wires to be twisted, a slidably mounted tail stock having means to hold said wires, a latch having one end adapted to engage said tail stock to retain it in its backward position, a table to receive material to be twisted between said wires, means for moving said table downwardly, and means connected with said table to engage said latch to remove it from the path of said tail stock.

20. A twisting machine comprising a rotatable spindle having means for holding wires to be twisted, a driving member mount-

ed on said spindle, clutch members for connecting said spindle and driving member, a pivotally mounted table, means for swinging said table on its pivot, and means actuated by the swinging movement of said table and connected with one of said clutch members for actuation thereof.

21. A wire twisting machine comprising a rotatable spindle having means for holding

wires to be twisted, a slidably mounted tail stock having means to hold said wires, means for retaining the tail stock in its backward position, a movably mounted table to receive material to be twisted between said wires, and a connection between said retaining means and said table for actuation of said retaining means.

ANTON VAN VEEN.
